LAMP FIXTURE

August O. Elting, Chicago, Ill.

Application October 9, 1939, Serial No. 298,584

4 Claims. (Cl. 248—200)

The invention relates to improvements in lamp fixtures and more particularly to a novelly constructed one-piece electric candle support or arm embodying novel mounting means.

5 An object of the invention is to provide one piece lamp fixture arms adapted to be held rigidly and securely against turning when mounted in a lamp fixture.

Another object of the invention is to provide 10 a one piece channelled arm embodying structural features adapting it to receive and conceal electric wires.

Another object is to provide an arm for a lamp 15 fixture assembly which, due to its novel features, will be inexpensive to manufacture and easy to attach to the fixture.

The foregoing and such other objects of the invention as will become more apparent as the description proceeds will be more readily understood 20 from a perusal of the following specification, in which reference is made to the accompanying drawing, wherein:

Fig. 1 is a fragmentary elevational view of a lamp fixture embodying the present invention.

25 Fig. 2 is a longitudinal sectional view taken through one of the arms and its mounting.

Fig. 3 is a sectional view taken substantially on line 3—3 of Fig. 2.

Fig. 4 is a bottom plan view of the arm.

30 Fig. 5 is a vertical sectional view taken on line 5—5 of Fig. 2.

Fig. 6 is a vertical sectional view similar to Fig. 2, showing another arm embodying features of the invention.

35 Fig. 7 is a vertical sectional view similar to Fig. 6, showing a modified form of arm.

In the drawing like numerals identify corresponding parts throughout the specification.

A known method of manufacturing an electric 40 candle support or arm and for securing it to a lamp fixture includes, forming a length of tubing into any desired shape and securing it to the hollow body of a lamp, either by threading one end to receive a lock nut or by swedging it.

45 It further includes the threading of the other end of the tubing to receive a lamp socket and the securing of a cup to the fitting. In some instances the known method includes the fitting of ornaments over the tubing between its ends and in 50 other instances the ornaments are cast around the tubing.

The known methods are costly and result in an inefficient article but in the method of the present invention expense is eliminated because the 55 cup is cast integral with the arm thereby elimi-

nating the tubing. Consequently, the arm may take any shape such as illustrated by way of examples in the various illustrations as disclosed in the drawing.

The shape the arm is to take is determined by 5 how it is to be mounted. By way of examples, the arm illustrated in Figs. 1 to 5 is arranged to be mounted on the bottom face of the lamp fixture body, the arm of Fig. 6 is arranged to be mounted in the top wall of the body and the arm 10 of Fig. 7 is arranged to be mounted on the side wall of the body.

Referring more particularly to Figs. 1 to 5 inclusive, the arm 11, as best illustrated in Fig. 2, includes an intermediate body portion 12 formed 15 with a top wall 13 and depending side walls 14. A flange 15 formed integrally with the arm extends inwardly from one end thereof and is provided with a square boss 17. External threads 20 are cast on said end and a hole 21, communicating with the channel, is formed while casting to provide a nipple 16.

To mount the arm, the nipple 16 and square boss 17 are inserted through a square opening 18 in the fixture body 19. A lock nut 20 then is 25 screwed tightly on said end to draw the flange 15 against the outside face of the body to hold the square boss 17 in register with the square opening 18, thereby holding the arm rigidly and 30 securely against turning.

A cup 23 is provided adjacent the free end of said arm and, as shown, the axial opening 27, cast therein is tapped to receive a nipple 26. A socket fitting or socket 25 is threaded onto said 35 nipple.

Both apertured ends of the cast arm admit electric wires 22. As shown, the wires lie snugly within the channelled body portion 12 and are adequately concealed by the side walls 14 and by depending end portions 28 and 29.

Obviously, arms constructed as described are decidedly less expensive to manufacture than those including brass tubing. It is also obvious that the arms are held rigidly in the body 19 against any turning movement although they 45 may be readily removed for replacement.

The S-shaped arm shown in Fig. 6 is structurally similar to the arm previously described except that in this instance the arm has its two ends extending in opposite directions so that it 50 may be mounted on the top face of the body 19. In this form the cast externally threaded end 16 is open on one side to facilitate withdrawal of the core, and it is necessary to provide a depending portion 29 at the free end 26 only.

The substantially straight arm shown in Fig. 7 has its ends disposed at right angles to each other and is adapted to be mounted on a vertical side wall of the fixture body 19. The cast externally threaded end 16 is also formed open at the bottom to facilitate withdrawal of the core. This arm also requires but one depending portion 29 to conceal the contents of the channelled body.

Although exemplary forms of the improved 10 one-piece cast arm have been illustrated and described it is to be understood that the disclosure is illustrative only and not restrictive and that the invention is to embody such a variety of modifications as will fall within the spirit of the invention 15 and the scope of the appended claims.

I claim:

1. A lamp fixture comprising, in combination, a fixture body and radial fixture arms, said arms each including an intermediate body portion providing an inverted wire-receiving channel, an externally threaded nipple at each arm end, both said nipples being in communication with said channel and at least one of the nipples being integral with the body portion, a cup integral with 25 the body portion below one end nipple, and an integral boss of non-circular section adjacent the other end nipple, the fixture body being provided with a plurality of openings corresponding in shape to that of the arm bosses, and said 30 other nipple of each arm extending through a body opening and secured to said body by a securing nut, said arm bosses and openings coacting to prevent turning of the arms upon their 35 securing to the fixture body.
2. A lamp fixture comprising, in combination, a fixture body and radially extending arms, said arms each including an intermediate body portion providing an inverted wire-receiving channel, an integral, externally threaded nipple on

one arm end in communication with the arm channel and having a squared boss, the other arm end having a tapped opening therein also in communication with the arm channel, a nipple threaded into said tapped opening, and a cup 5 integral with said body portion and disposed about said tapped end and the nipple associated therewith, the fixture body being provided with a plurality of square openings, the integral nipples each extending through a body opening 10 and secured to the body by a securing nut, the squared bosses each coacting with a square opening to prevent turning of the arms upon their securing to the body.

3. As an article of manufacture, a fixture arm 15 including a body portion providing an inverted channel, an integral, externally threaded nipple on one end of the arm in communication with the channel and having a boss of non-circular section, the other end of the arm being formed 20 to provide an opening also in communication with said channel, and a cupped flange integral with said body portion and disposed about said opening.

4. As an article of manufacture, a fixture arm 25 including a body portion providing an inverted channel, an integral, externally threaded nipple on one end of the arm in communication with the channel and having a boss of non-circular section, the other end of the arm having a tapped 30 opening therein also in communication with the channel and adapted to receive a nipple, a cupped flange integral with said body portion and disposed about the tapped opening, and an integral channel end wall depending from said other end 35 of the arm for concealing the relatively front end of the channel.

AUGUST O. ELTING.
